UNITED STATES PATENT OFFICE.

ALBERT SCHMID, OF ALLEGHENY, ASSIGNOR TO THE WESTINGHOUSE ELECTRIC AND MANUFACTURING COMPANY, OF PITTSBURG, PENNSYLVANIA.

ELECTRIC LOCOMOTIVE.

SPECIFICATION forming part of Letters Patent No. 498,577, dated May 30, 1893.

Application filed November 16, 1891. Serial No. 411,979. (No model.)

To all whom it may concern:

Be it known that I, ALBERT SCHMID, a citizen of the United States of America, and a resident of Allegheny, in the county of Allegheny and State of Pennsylvania, have invented certain new and useful Improvements 5 in Electric Machines, (Case No. 453,) of which the following is a specification.

The invention relates to the construction of 10 the class of electric motors especially adapted for propelling street cars.

The object of the invention is to produce an 15 efficient well-protected, durable slow-speed motor. It has been customary to propel street cars by means of electric motors geared to the axle of the car through an intermediate gearing. It is desirable to reduce the number of 20 gears required, but this necessitates that the motor itself should run at a slower speed.

By my invention the motor shaft may be 25 geared directly to the axle of the car truck.

The invention involves numerous improvements 30 in the details of construction of the motor and its frame. These will be described 25 in connection with the accompanying drawings.

In the drawings, Figure 1 is a plan and Fig. 2 a side elevation of a car-truck equipped with 35 two motors. Fig. 3 is a plan of one of the motors. Fig. 4 is a sectional elevation of one of the motors, the section being taken through the side of the frame. Fig. 5 is a vertical 40 transverse section showing the motor upon the axle. Fig. 6 is a detail.

Referring to the figures, A represents a 45 motor frame within which the motor itself is carried. This frame is constructed with two bearings a for receiving the armature-axle and with bearings b near one end for receiving 50 the axle of the car. These bearings are formed in the lower side of the frame, and the bearing blocks a' and b' are bolted beneath the frame for holding the parts in position. The end of 55 the frame which is remote from the car axle is supported from the truck frame a² by suitable springs or cushions A².

The field-magnet G is cylindrical in form 60 and is constructed of two semi-cylindrical sections f', f². These sections are respectively hinged to the frame at opposite ends 65 thereof in the following manner: Lugs d pro-

ject from the upper side of the frame A at one end, and these lugs receive corresponding lugs d' formed upon the upper portion of the field-magnet of the motor. The two parts are 55 then hinged together by means of a bolt. In like manner lugs e are formed on the under side of the frame on the end opposite the lugs d, and the corresponding side of the lower portion f² of the field-magnet is provided with 60 lugs e' which are hinged to the lugs e by a bolt passing through all of the lugs. The field-magnet sections when in position are bolted together by means of bolts k extending 65 through suitable lugs formed in the castings 70 for that purpose. A link l² may be fastened into the upper portion f' of the field-magnet in order to lift it and turn it back upon its hinge when desired, and when the bolts k are loosened.

It will be understood that by placing the 75 hinging lugs at opposite ends for the upper and lower portions of the field-magnet, each section may be readily swung back or outward when it is desired to obtain access to the armature. The lower section is shown as being 80 hinged to the portion remote from the axle of the car. This feature is of importance as it allows the section of the field-magnet to clear the car axle when turned back.

Each section of the field-magnet is provided 85 with two inwardly projecting pole-pieces g. The field-magnet coils for these pole-pieces are wound apart from the motor itself upon suitable spools and then placed 90 over the poles and there held in position by means of suitable bolts K, which extend from the spool through the field-magnet frame. They may be supported in any other suitable manner. I usually prefer to make the inwardly projecting pole-pieces of such dimensions as not to extend to the extreme edge of 95 the field-magnet frame, so that a sufficient portion of the field-magnet frame juts out beyond the sides of the pole-pieces to cover the armature coils.

The armature H is mounted upon a suitable 100 shaft passing through bearings a and it is provided with a suitable commutator h against which commutator brushes k', k', are held in any suitable manner. For the purpose of shielding and protecting the motor commu-

tator and the corresponding end of the motor a metal shield Q in the form of a section of a cylinder is placed at the end of the lower portion of the field-magnet and it may constitute 5 a continuation thereof. In this manner dirt and dust are shut away from the motor. A plate or guard P may protect the upper portion of the commutator and end of the motor.

Gear casings, R, such as are described in my 10 patent No. 442,459, dated December 9, 1890, and Design Patent No. 20,481, dated January 13, 1891, are also provided for incasing the pinion r and gear wheel R' which are respectively carried by the armature shaft and the 15 car axle.

I claim as my invention—

1. In an electric motor, the combination of a supporting frame, a field-magnet formed in two sections, one section hinged to one end of 20 the frame and the other section hinged to the other end of the frame.

2. In an electric motor, a supporting frame for carrying the armature and field-magnet, said field-magnet being constructed in two 25 sections, one section being hinged to the said frame upon its upper side at one end, and the other section being hinged to the said frame upon its lower side and at the other end.

3. In a motor for street cars, the combination of a field-magnet formed in two sections, a frame, to the opposite ends of which said sections are respectively pivoted and bearings formed in said frame for receiving the 30 axle of the car.

4. In a motor for street cars, the combination of a cylindrical field magnet having inwardly projecting poles, said field magnet being formed in two sections, a frame to which said sections are independently hinged and bolts normally holding said sections together. 40

5. In a motor for street-cars, a cylindrical field-magnet having inwardly projecting poles, removable separately-wound coils carried by the respective poles, said field-magnet being formed in sections, a frame to which the sections are pivoted upon opposite sides and at opposite ends, substantially as described. 45

6. In a motor for street cars, a frame consisting of side bars and the cross bars at the front and rear ends, one of said cross bars 50 having hinging lugs mounted upon its upper side and the other having hinging lugs mounted upon its lower side.

7. A frame for electric motors consisting of a single casting having upwardly extending 55 hinging lugs at one end and downwardly extending hinging lugs at the other end.

8. In a frame for electric motors for street cars bearings for the car axle at one end, and hinging lugs upon the under side of the frame 60 at the other end.

In testimony whereof I have hereunto subscribed my name this 6th day of November, A. D. 1891.

ALBERT SCHIMID.
